(57) CLAIM

The ornamental design for an extensible bed, as shown and described.

DESCRIPTION

FIG. 1 is an upper, left, front perspective view of the extensible bed showing our new design with the back in a seat position;

FIG. 2 is an enlarged view of FIG. 1 with the back in a seat position;

FIG. 3 is an upper, left, rear perspective view of the extensible bed with the back in a seat position;

FIG. 4 is an enlarged view of FIG. 3 with the back in a seat position;

FIG. 5 is an upper, left, front perspective view of the extensible bed with the back in a bed position;

FIG. 6 is an enlarged view of FIG. 5 with the back in a bed position;

FIG. 7 is an upper, left, rear perspective view of the extensible bed with the back in a bed position;

FIG. 8 is an enlarged view of FIG. 7 with the back in a bed position;

FIG. 9 is a left view of the extensible bed with the back in a seat position;

FIG. 10 a left view of the extensible bed with the back in a reclining position;

FIG. 11 a left view of the extensible bed with the back in a bed position;

FIG. 12 is a rear view of the extensible bed with the back in the seat position;

FIG. 13 is a top view of the extensible bed with the back in the seat position;

FIG. 14 is a front view of the extensible bed with the back in the bed position; and,

FIG. 15 is a top view of the extensible bed with the back in the bed position.

The broken lines are for environmental purposes only and form no part of the claimed design.
